RAUL DIEZ MURO, OF HABANA, CUBA.

BOTTLE.

1,146,809.

Specification of Letters Patent. Patented July 20, 1915.

Application filed March 13, 1914. Serial No. 824,448.

To all whom it may concern:

Be it known that I, RAUL DIEZ MURO, a citizen of Cuba, and a resident of Habana, Cuba, have invented a new and Improved 5 Bottle, of which the following is a full, clear, and exact description.

This invention relates to bottles, jars and the like having particular reference to sealing or closure means for such containers. It 10 will be understood, therefore, that the term "bottle" as used hereinafter for convenience of description is to be interpreted broadly enough to cover any kind of a jar or container adapted to be sealed or closed 15 by a means equivalent to that herein illustrated.

Among the special objects of the invention is to provide a bottle with a neck into which is fitted a stopper and providing a 20 locking means for said stopper which cannot be released without breaking a portion of the bottle neck.

The foregoing and other objects of the invention will hereinafter be more fully described and claimed and illustrated in the drawings forming a part of this specification in which like characters of reference indicate corresponding parts in all the views, and in which—

30 Figure 1 is a side elevation of the upper part of one form of the invention, partly in section, on the line 1—1 of Fig. 2; Fig. 2 is a side elevation of the same looking toward the right in Fig. 1; Fig. 3 is a modified 35 form of stopper; Fig. 4 is the upper end of a bottle neck adapted to receive the stopper shown in Fig. 3; Fig. 5 is a side elevation of a modified form of bottle; and Fig. 6 is a transverse sectional detail of the same, on 40 the line 6—6 of Fig. 5.

The several parts of the device may be made of any suitable materials, and the relative sizes and proportions, as well as the general design of the mechanism, may be 45 varied to a considerable extent without departing from the spirit of the invention hereinafter more fully set forth and specifically claimed.

The bottle neck 10 is formed with a mouth 50 11 adapted to receive a stopper 12, the engaging surfaces of the stopper and mouth being preferably ground or otherwise closely fitted to each other in order to seal the bottle. The stopper, as heretofore, is preferably provided with a finger piece 13 for manipulating it.

The stopper is shown provided with a hole 14 extending transversely through it but below the rim of the bottle mouth. The bottle neck 10 is also provided with a hole 15 60 registering with one end of the stopper hole 14 when the stopper is seated in proper position, and at the other side of the neck there is provided a seat 16 constituting the lower end of a slot 17 formed in or leading 65 downwardly from the upper edge or rim of the bottle neck. Said seat 16 alines, therefore, with the end of the hole 14 opposite the hole 15. The purpose of these holes formed in the stopper and bottle neck is to 70 accommodate a strong locking pin 18 of peculiar form, the same being adapted to be driven or forced through the holes 15, 14, and extending into the seat 16 as shown in Fig. 1. 75

A lug or projection 19 is formed integral with or otherwise rigidly secured to the outer wall of the bottle neck directly opposite the seat 16 or in alinement with the pin 18. The lug 19 serves as a stop to limit the 80 movement of the pin while it is being inserted into locking position. Any suitable means may be employed in connection with the pin to prevent its reverse movement from locking position. A catch 20 is shown in 85 this instance as constituting such locking means for the pin, the catch being V-shaped and carried within a seat or slot 21 in the pin 18, and comprising a finger 22 which, in the locking position of the pin, snaps downwardly or outwardly from the pin into a notch 23 formed in the stopper adjacent one 90 wall of the hole 14. The opposite portion of the catch 20 bears against the opposite wall of the hole 14 whereby the finger 22 is 95 caused to snap into said notch. It follows that with the pin and its locking device as shown in Fig. 1, the pin can not be withdrawn outwardly through the hole 15 and so long as the lug 19 remains intact the pin 100 can not pass outwardly the other way. The stopper, therefore, will be securely locked in position, sealing the bottle. In order to open a bottle thus sealed, a sharp tap or blow upon the lug 19 applied thereto either 105 directly or by striking against the projecting end of the pin 18 will cause the lug 19 to be broken off. The pin may, therefore, be forced through the seat 16 far enough for the said projecting end to pass the hole 15, 110 the catch 20 permitting such movement. The stopper may then be grasped and re-

moved directly outwardly from the bottle neck, the pin 18 moving upwardly along the slot 17. For this purpose the pin may be carried by the stopper or it may be driven 5 entirely from the stopper in this type of bottle.

In that form of the invention shown in Figs. 3 and 4, the stopper 12' is adapted to be fitted into the bottle neck 10' by a spiral 10 movement, the stopper being provided for this purpose with a spirally threaded surface. This surface requires that the stopper be rotated while being introduced or withdrawn. A slot 17' corresponding practically 15 to the slot 17 above described is formed in the bottle neck, but when used in connection with such bottle as requires the stopper to be removed while the locking pin is still engaged with it, said slot 17' must be formed 20 on a spiral corresponding to the form of the stopper. The stopper hole may be either horizontal or inclined and of any suitable cross sectional form. As shown in Fig. 3, the hole 14' is inclined slightly to the horizontal 25 but is adapted to receive a suitable locking device as in the other case. A lug 19 is shown adjacent the lower end of the slot 17' and serves the purpose already set forth in connection with the locking pin adapted to 30 be seated in the stopper and slot.

That form of the invention shown in Figs. 5 and 6 constitutes a compound bottle construction having a plurality of chambers or compartments 24 separated each from the 35 others by walls 25. Each of the compartments has its own neck 10" and locking device for a stopper 12. As shown in Fig. 5, the several necks 10" extend upwardly in some cases rather closely together and hence 40 this exemplifies the necessity for removing the stoppers individually without driving the locking pins 18 entirely through the stoppers. In other words, in the opening of any

one or more of the compartments of the compound structure of Fig. 5, a pin 18 will 4 be driven or forced far enough through the stopper to break off its protecting lug 19, but the movement of the pin would be checked by the remaining lugs 19 if an attempt were made to drive it much beyond 50 the inner end of the hole 15; hence the necessity for removing the stopper while the pin is carried thereby, the pin moving along the slot.

Having thus described my invention, I 55 claim as new and desire to secure by Letters Patent:—

The herein described bottle construction comprising a bottle having a neck provided with a slot leading downwardly from its upper edge and forming a seat at its lower end, a stopper fitted in said neck to seal the same, a locking pin extending through one wall of the neck and through the stopper into engagement with the opposite wall of the neck 60 and seated in said seat, said pin having a slot formed transversely through its middle portion, said stopper having a notch adjacent the locking pin and registering with said pin slot, a V-shaped spring catch located 70 within said pin slot to prevent the reverse movement of the locking pin, one end of the catch engaging in the stopper notch and the other end bearing against the opposite wall 75 of the stopper hole, and a frangible lug carried by the bottle neck and serving to prevent the movement of the pin along the direction in which it is inserted.

In testimony whereof I have signed my name to this specification in the presence of 80 two subscribing witnesses.

RAUL DIEZ MURO.
